No. 36,693.

Patented December 22, 1903.

UNITED STATES PATENT OFFICE.

JOHN E. LOWE, OF LEOMINSTER, MASSACHUSETTS, ASSIGNOR TO J. E. LOWE & SON, OF LEOMINSTER, MASSACHUSETTS.

DESIGN FOR A POMPADOUR-PUFF COMB.

SPECIFICATION forming part of Design No. 36,693, dated December 22, 1903.

Application filed November 16, 1903. Serial No. 181,449. Term of patent 3½ years.

To all whom it may concern:

Be it known that I, JOHN E. LOWE, a citizen of the United States, residing at Leominster, in the county of Worcester and State of Massachusetts, have invented a new, original, and ornamental Design for Pompadour - Puff Combs; and I do declare the following to be a full, clear, and exact description of the same.

My invention relates to a design for pompadour-puff combs, which is illustrated in the accompanying drawings, in which—

Figure 1 is a plan view; Fig. 2, a perspective view taken on an elevation.

What I desire to secure by Letters Patent is—

The ornamental design for a pompadour-puff comb, as shown.

JOHN E. LOWE. [L. S.]
